UNITED STATES PATENT OFFICE

2,424,519

NONNUMERICAL ROTARY HOMING
TYPE SWITCH

Reginald Taylor and George Thomas Baker, Liverpool, England, assignors to Automatic Electric Laboratories Inc., Chicago, Ill., a corporation of Delaware

Application December 11, 1944, Serial No. 567,551
In Great Britain February 1, 1944

10 Claims. (Cl. 179—18)

1

The present invention relates to telephone or like systems and is more particularly concerned with subscribers' line circuits of the type incorporating a forwardly hunting switch for connecting the subscriber's line with a first numerical switch which will subsequently respond to the first dialled digit. The general object of the invention is to provide a subscriber's line circuit suitable for satisfactory operation over very long lines and permitting toll breakdown facilities with the employment of only two relays of standard type with non-marginal operation.

According to one feature of the invention, in a subscriber's line circuit comprising a line relay and a cut-off relay and a non-numerical switch of the rotary homing type giving access to a group of first numerical switches, during outgoing calls the application of potential to the guarding conductor extending to the final selectors over which incoming calls are completed is made by way of the low resistance winding of the cut-off relay and a wiper of the switch in off-normal position in order to enable the relay to be released by the application of direct guarding potential from a final selector.

According to another feature of the invention, in a subscriber's line circuit comprising a line relay and a cut-off relay and a non-numerical switch of the rotary homing type giving access to a group of first numerical switches, the guarding conductor extending to the final selectors over which incoming calls are completed is connected to an auxiliary wiper of the rotary switch and the contact engaged by this wiper in normal position is connected to one terminal of the cut-off relay which is also arranged to be connected to the guarding and holding wiper of the switch throughout an outgoing connection while the contacts engaged by the auxiliary wiper when in off-normal position are connected to the other terminal of the cut-off relay so that the connection of the same potential to the guarding conductor in the final selector will produce operation or release of the cut-off relay according as the switch is in normal or off-normal position.

The invention will be better understood from the following description of one method of carrying it into effect which should be taken in conjunction with the accompanying drawings comprising Figs. 1-3. Of these Fig. 1 shows details of a subscriber's line circuit employing a so-called uniselector embodying the invention, while Figs. 2 and 3 when arranged side by side show the circuit of a modified numerical switch of the 200-outlet type arranged for operation as a first

2

selector and assumed to be directly accessible from the uniselector of Fig. 1.

Considering first the operation of the uniselector of Fig. 1 on an outgoing call, when the line SL is looped by the subscriber removing his receiver, relay L is operated from earth at contacts K4 over wiper D1 of the uniselector in normal position, subscriber's loop, contacts K1, common lead 10 to battery by way of one of the alternative connections the purpose of which will be described subsequently. Relay L thereupon energises and at contacts L1 completes a locking circuit for itself independently of wiper D1, and at contacts L2 and L3 completes a circuit over wiper D3 in normal position for the uniselector driving magnet DM by way of its interrupter contacts DMC. Earth supplied by contacts L3 also extends to one side of the meter and over wiper D2 in normal position to the private normal conductor extending to the final selector bank so as to busy the line against incoming calls. Relay K is short-circuited at this time over contacts L2 and K2 and wiper D3. The magnet now operates and opens its interrupter contacts whereupon it releases and advances the wipers into engagement with the first outgoing line. If this line is busy, wiper D3 encounters earth and the driving circuit and also the short-circuit on relay K are maintained. When a free line is reached, wiper D3 fails to encounter earth and relay K operates in series with magnet DM which cannot now energise. Relay K at contacts K1 disconnects relay L and connects up the negative wiper D5, at contacts K3 connects up the positive wiper D4, at contacts K2 prepares a locking circuit for itself to the P conductor and at contacts K4 opens another point in the circuit of relay L and provides the operating earth for the meter which it will be noted is now short-circuited. Relay L is made sufficiently slow to release to cover the time required for earth to be fed back over the P conductor from the seized first numerical switch so as to maintain relay K and the guard on the private normal conductor. It will be noted that as soon as the switch steps off-normal the direct earth initially provided on this latter conductor is replaced by earth through the winding of relay K which is accordingly of sufficiently low resistance to make this guarding effective.

When the connection is fully set up and the called party replies, metering is effected by the connection of booster battery to the P lead in well-known manner whereupon the meter MTR operates to register the call. The rectifier MRA

is provided to obviate any tendency for the meter to remain operated in series with relay K when the connection is released.

When the calling party hangs up at the end of the conversation, the holding earth which has been supplied to the P conductor from the final selector or outgoing repeater is removed and relay K falls away. A homing circuit is then completed over contacts K4 and L2 and wiper D1 and the uni-selector steps on to its normal position.

On an incoming call earth is applied to the normal conductor extending from the final selector multiple FSM through both windings of a double-wound switching relay in the final selector. If the line is idle, this earth extends over wiper D2 in normal position, winding of relay K, resistance KYA, interrupter contacts DMC and winding of magnet DM to battery. The switching relay in the final selector thereupon operates and short-circuits one of its windings so as to apply low resistance earth to the P conductor to guard the line and also to operate relay K which thereupon disconnects relay L in order to prevent its operation when the called party removes his receiver. When the connection is subsequently released, earth is removed from the P conductor and relay K restores to normal.

If a toll call arrives for the subscriber at a time when he is busy, the operator may effect connection with the line circuit over her toll breakdown final selector and then converse with the party and inform him that a toll call is waiting. If she then institutes toll breakdown conditions, full earth is applied to the P conductor.

Considering first the case in which the party desired is the calling party in the established connection, his uniselector will be off-normal and the breakdown earth on the P conductor will therefore short-circuit relay K and cause its release but will not operate the magnet DM owing to the presence of the resistance KYA in the circuit. The release of relay K opens the loop forward so as to release the existing connection and since relay L is de-energized at this time a homing circuit is completed for the uniselector. When the switch reaches normal position, circuits are completed for both relays K and L but since relay L is provided with a small armature end slug, relay K operates first and opens the circuit of relay L. Relay K then performs its normal functions on an incoming call.

If the wanted party is the called subscriber in the existing connection, the toll breakdown earth will maintain the already operated relay K and will force down the switching relay in the final selector of the train already set up.

It may be mentioned that a toll tone is usually provided on toll calls so as to notify the operator and warn her not to break down an existing toll connection. This tone is connected to the P conductor and in order to secure that it shall pass satisfactorily, it may be desirable to shunt relay K with a condenser of suitable size.

As previously mentioned, alternative facilities are provided for connection of the common lead 10 either direct to battery by way of the jumper represented by lines and circles or to battery via the key LDK by way of the jumper represented by lines and crosses. It will be appreciated that if the key LDK is operated the subscribers concerned will be unable to make outgoing calls as their line relays cannot then be operated. The purpose of the arrangement is to permit the cut-

ting off of subscribers not entitled to priority service so that priority subscribers will be able to make calls even if the exchange should become temporarily overloaded during emergency conditions.

It will be understood that the circuit for the line relay over a wiper of the uniselector, which prevents operation of the relay until the switch reaches the home position, could alternatively be included in the battery leg rather than the earth leg. This arrangement would have the possible advantage that in the event of an earth fault on the positive speaking wire, which would not necessarily put the line out of action, the line relay would still be prevented from operating until the switch reached normal position which would not be the case with the circuit shown.

In order to render the line circuit suitable for 20 operation over long lines, it is desirable to have as much winding space as possible on the L relay and if standard components are to be used this means reducing the size of the slug ordinarily employed to give this relay its slow releasing characteristic. As a result the lag on the relay will be reduced but this may be safely done if arrangements are provided whereby the holding earth is fed back from the first selector switch with the least possible delay. This is effected by the modified selector switch shown in Figs. 2 and 3 which is arranged so that earth is fed back on the operation of relay A and is subsequently reinforced by earth provided by the so-called guard or release relay B. The switch of Figs. 2 and 3 is otherwise similar to that shown in our Patent No. 2,137,423 granted November 22, 1938, and its operation will now be traced through briefly.

When the selector switches through, relay A 40 operates over the loop by way of its upper and lower windings and applies an immediate earth to the P conductor over contacts C5, N2, A1 and N4. Relay A also at these same contacts A1 energises relay B in series with vertical magnet VM and resistance YA. Relay B thereupon completes a locking circuit for itself at contacts B1, energises relay C by way of its upper winding at contacts B2, and reinforces the earth on the P conductor at contacts B3. Relay B also at contacts B4 completes a circuit for the supervisory lamp LP over common lead 25 which extends to delayed alarm equipment, at contacts B5 prepares circuits for relays HA and HB, at contacts B6 connects up dial tone from common lead 23 to the middle winding of relay A whence it is transmitted by induction to the line windings and at contacts B7 opens a point in the release circuit. Relay C at contacts C1 prepares a circuit for its lower winding, at contacts C2 closes another point in the circuit for relays HA and HB, at contacts C3 and C6 closes points in the speaking leads, at contacts C5 opens the initial circuit for relay B and at contacts C4 opens a point in the circuit of the rotary magnet RM.

The switch is now in a condition to respond to dialled impulses and when these are transmitted relay A operates accordingly. On the first release of relay A, a circuit is completed for the vertical magnet VM by way of contacts B1, A1, NR4, C1, lower winding of relay C, winding of vertical magnet VM to battery. The switch wipers are therefore raised one step and the off-normal contacts are operated whereupon at contacts N1 relays HA and HB are operated over their middle windings. Thereupon at contacts

HA1 and HB2 they complete a locking circuit for themselves while at contacts HA3 and HB6 the upper winding of relay C is short-circuited. This relay, however, continues to hold up throughout the train of impulses due to the intermittent energisation of its lower winding in series with magnet VM.

On the termination of the impulse train, relay C releases and at contacts C4 completes a circuit for the rotary magnet. This accordingly advances the wipers into engagement with the first set of contacts and the normal rotary contacts are open operated. Moreover, when the rotary magnet completes its stroke the interrupter contacts RMC are opened, thereby interrupting the circuit for the magnet and also the initial circuit for relays HA and HB. If, however, both the lines now engaged by the two sets of wipers are busy, wipers P1 and P2 will both encounter earth and relays HA and HB will be maintained over their right-hand windings. Accordingly, when contacts RMC again close on the de-energisation of the rotary magnet, a further energising circuit is completed and the wipers are advanced a further step. This continues until an idle line is found or the wipers are driven to the overflow position.

If the upper set of wipers encounters a free line and the lower set a busy line, relay HB releases owing to the failure of wiper P1 to find earth and at contacts HB5 applies immediate guarding earth from contact B3 to busy the line seized. Moreover, at contacts HB6 the short-circuit is removed from relay C which therefore now operates and a holding circuit is completed for relay HA from earth, contacts B3, HB2, left-hand winding of relay HA, contacts NR4, C1, lower winding of relay C, winding of vertical magnet VM to battery. At contacts C3 and C6 the speaking leads are switched through in conjunction with contacts HA2 and HA6 and the former contacts also disconnect relay A which now releases and short-circuits relay B which also releases after a slight interval. Earth is now fed back over wiper P1 from the succeeding switch to maintain relay HA and also relay K in the subscriber's line circuit while relay C is maintained over contacts HA1.

If on the other hand the upper set of wipers engages a busy line and the lower set a free line, relay HA de-energises and at contacts HA5 provides an immediate guard for the seized line. Contacts HB6 and HA3 in this case provide the circuit for relay C and relay HB is held up over its left-hand winding by way of contacts HB2 and HA1 and the circuit to battery through relay C and magnet VM as previously traced.

If both sets of wipers encounter free lines, relays HA and HB both de-energise and guarding earth is applied to wiper P1 over contacts B4. In these circumstances, on the re-operation of relay C over contacts B2, a circuit is completed for relay HA as previously traced but no circuit is completed for relay HB so that the upper set of wipers has preference.

If all the lines in the selected level are busy, the wipers advance to the 11th position in which the S contacts are operated. Thereupon at contacts S2 earth is extended over wiper P1 to lead 26 which is connected to an overflow meter, at contacts S1 busy tone over lead 22 is connected up in place of dial tone and at contacts S3 busy flash in the form of alternate battery and earth connections is connected to the middle and lower windings of relay A to give the necessary signal in case the call has been set up by an operator.

When release is to take place at the end of the connection, earth is removed from the P conductor to permit the release of relay HA or HB as the case may be. Relay C is also then released and a circuit for the rotary magnet is completed by way of contacts C4, N1, RMC, C2, B7 and link T to common lead 24 which extends to earth by way of release alarm equipment. The wipers are then advanced to 12th position in which they move clear of the bank, fall and rotate to normal underneath it in well-known manner.

It is important for the purpose of securing an immediate holding earth that relay A should operate as rapidly as possible. This relay however may be energised over a very long line and therefore its spring load must be reduced as far as possible. It will be seen that relay A still has only one spring combination which is used for operating relay B and subsequently repeating impulses and the additional holding function is also performed by this spring combination.

The invention therefore provides an improved line circuit which gives additional facilities without increasing the amount of equipment required while at the same time there is no sacrifice of reliability of operation.

We claim:

1. In a telephone or like system, a subscriber's line circuit comprising a cut-off relay and a non-numerical switch of the rotary homing type giving access to a group of first numerical switches, a wiper on said switch, a guard lead for said circuit connected to said wiper, means including said wiper and a potential connected directly to said guard lead for operating said cut-off relay in case said rotary switch is connected to one of said numerical switches, means responsive to the operation of said cut-off relay for restoring said rotary switch to its home position, and means including said wiper and said potential for further operating said cut-off relay after said rotary switch has reached its home position to maintain said rotary switch therein.

2. In a telephone or like system, a subscriber's line, a line circuit therefor comprising a cut-off relay and a rotary switch, a group of trunk circuits accessible to said rotary switch, a wiper on said rotary switch having a guard lead for said line circuit connected thereto, means for operating said cut-off relay in response to the connection of said rotary switch to one of said trunk circuits to connect said line thereto and to extend a guarding potential to said guard lead through the winding of said cut-off relay and said wiper, means for releasing said cut-off relay in response to the connection of a similar potential directly to said guard lead to disconnect said line from said trunk circuit.

3. In a telephone or like system, a subscriber's line, a line circuit therefor comprising a relay and a rotary switch having a normal position, a group of automatic switches accessible to said rotary switch, a wiper on said rotary switch having a guard lead for said line circuit connected thereto, means for operating said relay in response to the connection of said rotary switch to one of said automatic switches to connect said line thereto and to extend a guarding potential to said guard lead through the winding of said relay and said wiper, means for releasing said relay in response to the connection of a similar potential directly to said guard lead to disconnect said line from said automatic switch, means responsive to the release of said relay for restoring said rotary switch to its normal position, and means effective

thereafter for operating said relay to maintain said rotary switch in its normal position, said last means including said similar potential and said wiper.

4. In a telephone or like system, a rotary switch having a home position, a wiper on said switch, a guard lead connected to said wiper, one contact engaged by said wiper with said switch in its home position, other contacts for engagement by said wiper in case said switch is moved from its home position, a relay, means including said wiper and said one contact for operating said relay in one manner from a potential applied to said guard lead with said switch in its home position, and means including said wiper and one of said other contacts for operating said relay in another manner from a similar potential applied to said guard lead in case said switch is off normal.

5. In a telephone or like system, a rotary switch having a normal position, wipers on said switch, normal contacts engaged by said wipers with said switch in its normal position, other contacts engaged by said wipers with said switch off normal, a line relay having a starting circuit including one of said wipers and one of said normal contacts, a cut-off relay having a starting circuit including another of said wipers and another of said normal contacts whereby said starting circuits are disabled in case said switch is off normal, a group of automatic switches, means including said line relay for establishing a connection between said rotary switch and one of said automatic switches, means for operating said cut-off relay in response to said connection, means including said other wiper and one of said other contacts for releasing said cut-off relay, means for releasing said connection and for restoring said rotary switch to its normal position in response to the release of said cut-off relay, said wipers being effective to prevent the closure of said starting circuits while said rotary switch is off normal.

6. A telephone or like system as set forth in claim 5 in which said cut-off relay operates thereby preventing the operation of said line relay in case both of said starting circuits are closed at the same time.

7. A telephone or like system as set forth in claim 5 in which said one wiper included in the starting circuit for the line relay is also included in the means for restoring said rotary switch to its normal position.

8. In a telephone or like system, a subscriber's line, a line circuit comprising a line relay and a cut-off relay and a non-numerical switch of the rotary homing type giving access to a group of numerical switches, means including said switch for establishing a connection between said line and one of said numerical switches, said cut-off relay being operated and said non-numerical switch being in a non-home position during said connection, a relay in said numerical switch operated over said line immediately said connection is established to connect a holding circuit to said cut-off relay, a guard lead for said line circuit, means including said guard lead responsive to the extension of another connection to the line

for releasing said cut-off relay in case said line is connected to one of said numerical switches, to thereby disable said connection to the numerical switch.

9. In a telephone system, a subscriber's line, a line circuit therefor comprising a line relay and a cut-off relay and a rotary switch having a normal position, said line relay being operative responsive to the closure of said line, a group of trunk circuits, means responsive to the operation of said line relay for operating said switch to seize one of said trunk circuits, said cut-off relay operated thereafter under control of said line relay to disable same and to connect said line to said one trunk circuit, a relay in said one trunk circuit operated in series with said line to connect a potential to said cut-off relay to hold it operated, slow release means in said line relay whereby it remains operated to hold said cut-off relay until said potential is connected thereto, a wiper on said switch, a guard lead connected to said wiper, means for connecting said potential through the winding of said cut-off relay and said wiper to said guard lead thereby making it a guarding potential for said line circuit, means responsive to the connection of a similar potential directly to said guard lead for releasing said cut-off relay to release said one trunk circuit and to disconnect said line therefrom, means responsive to the release of said cut-off relay for restoring said switch to its normal position, and means effective thereafter and including said wiper and said potential connected directly to said guard lead for operating said cut-off relay to maintain said switch in its normal position.

10. In a telephone or like system, a subscriber's line, a line circuit comprising a line relay and a cut-off relay and a rotary switch having a normal position, a group of automatic switches, a key having normally closed contacts, an operating power source connected to said line relay through said contacts, in case said key is normal said line relay being operative in response to the initiation of a call on said line to control the connection of said rotary switch and said line to one of said automatic switches, in case said key is operated said line relay being inoperative to thereby disable said line for the extension of outgoing calls, a wiper on said rotary switch, a guard lead connected to said wiper, means including said wiper and said cut-off relay and effective in case a connection is established between said line and one of said automatic switches for releasing said connection in response to the connection of ground directly to said guard lead.
